UNITED STATES PATENT OFFICE.

HAROLD F. ELLIOTT, OF PALO ALTO, CALIFORNIA, ASSIGNOR TO AUGUSTUS TAYLOR,
OF SAN FRANCISCO, CALIFORNIA.

RADIOTELEGRAPHY.

1,399,945.

Specification of Letters Patent.

Patented Dec. 13, 1921.

Application filed July 24, 1920. Serial No. 398,757.

To all whom it may concern:

Be it known that I, HAROLD F. ELLIOTT, a citizen of the United States, and a resident of Palo Alto, county of Santa Clara, and 5 State of California, have invented certain new and useful Improvements in Radiotelegraphy, of which the following is a specification.

The invention relates to a transmission 10 system of radio telegraphy and particularly continuous oscillation radio telegraphy, involving variations in antenna inductance.

An object of the invention is to provide 15 a signaling system in which the voltage and current applied to the signaling keys may be regulated.

Another object of the invention is to provide 20 a signaling system wherein the load is equally divided among a plurality of keys, the load on each key being such that sparking is avoided.

The invention possesses other advantageous features, some of which, with the foregoing, will be set forth at length in the following 25 description where I shall outline in full, that form of the invention which I have selected for illustration in the drawings accompanying and forming part of the present specification. In said drawings I 30 have shown one specific form of the system of my invention, but it is to be understood that I do not limit myself to such form, since the invention, as expressed in the claims, may be embodied in a plurality of 35 forms.

Referring to said drawings:

Figure 1 is a diagrammatic representation 40 of a radio telegraphy transmission system embodying my invention.

Fig. 2 is a diagrammatic representation of one form of loop system of my invention.

Fig. 3 is a sectional elevation of the system shown in Fig. 2.

Fig. 4 is a sectional elevation of a modified 45 form of system.

Fig. 5 is a diagrammatic representation of a modified form of system.

Fig. 6 is a diagrammatic representation of 50 a system involving closer coupling of the signaling circuits.

One method of signaling with continuous oscillations consists in varying the antenna

inductance, which variation produces a variation in wave length of the radiated wave, and to produce a given percentage change in 55 wave length the antenna inductance must be changed a certain amount. The antenna current through the inductance changed sets up a certain voltage which, multiplied by the antenna current, gives the kilo-volt-amperes 60 to be handled by the key or relay or other signaling instrument. On account of practical considerations, the kilo-volt-amperes which can be handled by one pair of contacts is limited and hence it is necessary to 65 employ a plurality of pairs of contacts.

In the system of the present invention, I employ a plurality of pairs of contacts and divide the load equally among the pairs of contacts and so adjust the elements of the 70 system that each pair of contacts carries the maximum load possible without sparking. I am, therefore, able to employ the minimum number of pairs of contacts, while maintaining perfect operating conditions at each 75 pair.

One form of continuous oscillation transmission system may be represented by a Poulsen arc 2, supplied with current from a direct current generator 3, and subjected 80 to a strong transverse magnetic field produced by the coils 4. One side of the arc is grounded and the other side is connected to the antenna 5, through the variable inductance or loading coil 6. Arranged in inductive relation with the coil 6, and preferably arranged adjacent the lower turn of the coil, are a plurality of separate loop circuits 85 7, substantially sector shaped, with the outer part 8 of each loop concentric with the axis 90 of the coil 6 and preferably of the same radius as the coil. Each loop may consist of one or more turns of the conductor and in practice I employ two or three turns, which causes the load on each individual key to be 95 the maximum load possible, without sparking at the contacts. The sides 9 of the loops are radially disposed with relation to the axis of the coil 6 and the loops are arranged in overlapping relation. Each loop is provided with a key or pair of contacts 10 and means are provided for opening and closing all of the contacts simultaneously, or substantially so. In the drawings I have shown

one contact of each pair connected to a solenoid 11, all of the solenoids being arranged in a circuit containing a battery and a signaling key.

- 5 The plurality of loops act as the secondary of a step-down transformer and the voltage in each loop is much lower than the voltage in the loading coil. By arranging the loops in overlapping relation and insulated from 10 each other, current in one loop does not induce current in the adjacent loops and, therefore, the contacts in each loop handle only the predetermined proportion of the load for which they are arranged. A further 15 advantage of overlapping the loops is that such construction permits each loop to be made larger than if the loops were spaced apart circumferentially to reduce mutual inductance, permitting each loop to inclose 20 more flux from the loading coil without excessive close coupling.

Since the loops overlap, a portion of the magnetic flux caused by current in one loop will cut the adjacent loop. However, the 25 voltage induced in the adjacent loop by the current flowing in the side 9 of the loop will be neutralized by the voltage induced in the opposite direction by the current flowing in the ends 12 and 13 of the loop. 30 The amount of overlapping may be readily determined, so that current in one loop will not induce a voltage in the adjacent loop. This may be done by connecting a voltmeter across the terminals of one loop, closing the 35 adjacent loop and then varying the amount of overlapping so that opening and closing of the adjacent loop will not vary the voltmeter reading.

It is desirable to effect a close coupling 40 between the loops and the loading coil so that the maximum number of lines of force will traverse the loop circuits, but it is also desirable to reduce the current load on the key units to maintain it below the maximum 45 non-sparking load. The current load on each key unit may be decreased, by inserting a resistance 14 in each loop circuit in series with the key, and the value of the resistance is so adjusted that a reduction in the power 50 delivered to the antenna is obtained when the resistance is effective in the circuit. The percentage of reduction of power is dependent upon the amount of resistance in the loop circuits and upon other electrical relations between the coupled loops and the main loading inductor. The insertion of 55 resistance in the loop circuits not only reduces the current through the key units but also, when the resistance is effective decreases 60 the amplitude of the radiated waves and reduces interference from the compensating wave.

When large loading inductors are used, such as those installed in high power stations, it is sometimes difficult to obtain the 65

proper coupling between the inductor and the loops, and I have provided means for producing better control of the coupling between these elements. Arranged within the circle of the loops and preferably in the 70 plane thereof, is a short circuited turn or loop 15 which is effective in increasing the magnetic flux through the key loops for any given location of the key loops with respect to the main loading inductor. The short 75 circuited loop or winding may comprise a single loop or a plurality of turns.

Assuming that the main flux from the loading coil is in a downward direction at a given instant, as shown by the arrows in 80 Fig. 3, a current will flow in the short circuited winding 15 which will set up a flux through the center of the winding approximately in opposition to the flux of the main loading coil. The magnetic flux surrounding the conductor of the short circuited winding will cut the inner ends of the key loops in the same direction as the flux from the loading coil, thereby increasing the flux through the key loops, providing a 90 closer coupling to the main coil.

When desirable the short circuited turn may be extended upward into the inductor 95 6 to obtain a variable coupling between the main loading coil and the short circuit winding, as shown in Fig. 4. Connected in series with the short circuit winding 15 is a winding 16 disposed within the coil and which is threaded by the loading coil flux. The use of this arrangement makes it possible 100 to regulate the load impressed on the signaling system and gives control of the voltage and current on the key units for any wave-length over the entire range of operation of the transmitting station. 105

In some instances it may be desirable to connect a variable reactor 17 in series in the short circuit winding to regulate the current through it and thereby regulate the load on the keys. 110

Instead of coupling the key loops directly with the main loading coil, the primary 18 of an air core transformer may be arranged in the antenna circuit and the key loops may form the secondary of such transformer. 115 The unit resulting from this construction is an air core alternating current transformer having a secondary winding composed of a plurality of isolated sector circuits, arranged to have the same inductive relation to the primary, but so arranged that the inductive coupling between the individual sections is neutralized.

To obtain a more close coupling with the loading coil, the windings thereof may be 125 spaced apart at one point and the key loops inserted between the spaced parts of the coil as shown in Fig. 6. The principal advantages of this arrangement are that the coupling remains more constant over a big 130

variation in wave length of the system and that better control is obtained for the power supply to the key units.

I claim:

5. 1. A radio telegraphy transmission system including an antenna circuit, an inductance coil in said circuit, a plurality of isolated overlapping sector circuits inductively connected to said inductance coil, and means 70 for opening and closing the sector circuits.
10. 2. A radio telegraphy transmission system, including an antenna circuit, an inductance coil in said circuit, a plurality of overlapping isolated circuits arranged in the 75 same inductive relation to said inductance coil, and means for opening and closing said isolated circuits.
15. 3. A radio telegraphy transmission system, including an antenna circuit, an inductance coil in said circuit, a plurality of overlapping isolated circuits arranged in the same inductive relation to said inductance coil, a variable resistor in each isolated circuit and means for opening and closing the isolated circuits. 80
20. 4. A radio telegraphy transmission system, including an antenna circuit, an inductance coil in said circuit, a plurality of overlapping isolated circuits arranged in the same inductive relation to said inductance coil, the circuit being so overlapped that a current in one coil induces no voltage 85
25. in the overlapping coil and means for opening and closing said isolated circuits.
30. 5. A radio telegraphy transmission system, including an antenna circuit, an inductance coil in said circuit, a plurality of isolated overlapping sector circuits arranged in the same inductive relation to said inductance coil, and means for opening and closing said isolated circuits. 90
35. 6. A radio telegraphy transmission system, including an antenna circuit, an inductance coil in said circuit, a plurality of overlapping isolated sector circuits inductively connected to said inductance coil, each sector circuit comprising a plurality of 95
40. turns of conductor, and means for opening and closing said isolated circuits.
45. 7. A radio telegraphy transmission system including an antenna circuit, an inductance coil in said circuit, a plurality of loop circuits inductively connected to said inductance coil, a resistor in each loop circuit and means for opening and closing the loop circuits. 100
50. 8. A radio telegraphy transmission system including an antenna circuit, an inductance coil in said circuit, a plurality of loop circuits arranged in the same inductive relation to said inductance coil, a resistor in each loop circuit and means for opening 105
55. and closing the loop circuits.
60. 9. A radio telegraphy transmission system including an antenna circuit, an inductance coil in said circuit, a plurality of isolated loop circuits arranged in the same inductive relation to said inductance coil, a resistor in each loop circuit and means for opening 110
65. and closing the loop circuits.
10. 10. A radio telegraphy transmission system including an antenna circuit, an inductance coil in said circuit, a plurality of loop circuits inductively connected to said inductance coil, a variable resistor in each loop circuit and means for opening and closing said loop circuits. 115
11. 11. A radio telegraphy transmission system including an antenna circuit, an inductance coil in said circuit, a plurality of isolated sector circuits arranged in the same inductive relation to said inductance coil, a variable resistor in each isolated circuit and means for opening and closing the isolated circuits. 120
12. 12. A radio telegraphy transmission system including an antenna circuit, an inductance coil in said circuit, a plurality of loop circuits inductively connected to the inductance coil, a short circuited coil inductively connected to said inductance coil and said loop circuits, and means for opening and closing the loop circuits. 125
13. 13. A radio telegraphy transmission system including an antenna circuit, an inductance coil in said circuit, a plurality of loop circuits arranged in the same inductive relation to said inductance coil, a short circuited coil inductively connected to said inductance coil and to said loop circuits, and means for opening and closing said loop circuits. 130
14. 14. A radio telegraphy transmission system including an antenna circuit, an inductance coil in said circuit, a plurality of loop circuits arranged in the same inductive relation to said inductance coil, a short circuited coil inductively connected to said inductance coil and said loop circuits, and means for varying the effect of the loop circuits on the inductance coil.
15. 15. A radio telegraphy transmission system including an antenna circuit, an inductance coil in said circuit, a plurality of isolated loop circuits arranged in the same inductive relation to said inductance coil, a short circuited coil inductively connected to said inductance coil and said loop circuits, and means for varying the effect of the loop circuits on the inductance coil. 135
16. 16. A radio telegraphy transmission system including an antenna circuit, an inductance coil in said circuit, a plurality of circumferentially disposed loop circuits inductively connected to the inductance coil, a short circuited coil arranged within the circle of the loop circuits and means for varying the effect of the loop circuits on the inductance coil.
17. 17. A radio telegraphy transmission sys-

tem including an antenna circuit, an inductance coil in said circuit, a plurality of circumferentially disposed loop circuits inductively connected to the inductance coil, a short circuited coil arranged within the circle of the loop circuits and means for opening and closing the loop circuits.

18. A radio telegraphy transmission system including an antenna circuit, an inductance coil in said circuit, a plurality of circumferentially disposed loop circuits arranged in the same inductive relation to the inductance coil, a short circuited coil arranged within the circle of the loop circuits and means for opening and closing the loop circuits.

19. A radio telegraphy transmission system including an antenna circuit, an inductance coil in said circuit, a plurality of isolated circumferentially disposed loop circuits arranged in the same inductive relation to the inductance coil, a short circuited coil arranged within the circle of the loop circuits and means for opening and closing the loop circuits.

20. A radio telegraphy transmission system including an antenna circuit, an inductance coil in said circuit, a plurality of circumferentially disposed loop circuits arranged in a plane perpendicular to the axis of the coil and in the same inductive relation thereto, a short circuited coil arranged within the circle of and in the plane of the loop circuits, and means for opening and closing the loop circuits.

21. A radio telegraphy transmission system including an antenna circuit, an inductance coil in said circuit, a plurality of circumferentially disposed isolated loop circuits arranged in a plane perpendicular to the axis of the coil and in the same inductive relation thereto, a short circuited coil arranged within the circle of and in the plane of the loop circuits, and means for opening and closing the loop circuits.

22. A radio telegraphy transmission system including an antenna circuit, an inductance coil in said circuit, a plurality of circumferentially disposed loop circuits arranged in a plane perpendicular to the axis

of the coil and in the same inductive relation thereto, a short circuited winding having a coil arranged within the circle of and in the plane of the loop circuits and a coil arranged within the inductance coil, and means for varying the effect of the loop circuits on the inductance coil.

23. A radio telegraphy transmission system including an antenna circuit, an inductance coil in said circuit, a plurality of circumferentially disposed loop circuits arranged in a plane perpendicular to the axis of the coil and in the same inductive relation thereto, a short circuited winding having a coil arranged within the circle of and in the plane of the loop circuits and a coil arranged within the inductance coil, and means for opening and closing the loop circuits.

24. A radio telegraphy transmission system including an antenna circuit, an inductance coil in said circuit, a plurality of loop circuits inductively connected to the inductance coil, a short circuited winding having a coil inductively connected to the loop circuits and a coil lying within the inductance coil, and means for opening and closing the loop circuits.

25. A radio telegraphy transmission system including an antenna circuit, an inductance coil in said circuit, a plurality of loop circuits inductively connected to the inductance coil, a short circuited coil inductively connected to the inductance coil and the loop circuits, a reactor in the circuit of the short circuited coil, and means for varying the effect of the loop circuits on the inductance coil.

26. A radio telegraphy transmission system including an antenna circuit, an inductance coil in said circuit, a plurality of loop circuits inductively connected to the inductance coil, a short circuited coil inductively connected to the inductance coil and the loop circuits, a variable reactor in the circuit of the short circuited coil, and means for varying the effect of the loop circuits on the inductance coil.

In testimony whereof, I have hereunto set my hand.

HAROLD F. ELLIOTT.
